US00D432934S

United States Patent [19]

Simbeck et al.

[11] Patent Number: Des. 432,934

[45] Date of Patent: ** Oct. 31, 2000

[54] ELECTRIC METER FACE COVER

[75] Inventors: Werner Reinhard Simbeck, Mill Bay; I. Ross Macfarlane; Markus F. Hirschbold, both of Victoria, all of Canada

[73] Assignee: Power Management Ltd., Canada

[**] Term: 14 Years

[21] Appl. No.: 29/108,224

[22] Filed: Jul. 21, 1999

[51] LOC (7) Cl. 10-04

[57] CLAIM

The ornamental design for an electric meter face cover, as shown and described.

DESCRIPTION

FIG. 1 is a right front perspective view of the electric meter face cover of the invention;

FIG. 2 is a front elevation of the electric meter face cover illustrated in FIG. 1;

FIG. 3 is a top view thereof the bottom view being a mirror image;

FIG. 4 is a left side view thereof;

FIG. 5 is a right side view thereof;

FIG. 6 is the rear end view thereof; and,

FIG. 7 is a front perspective view of the electric meter face cover with buttons.

CERTIFICATE OF CORRECTION

PATENT NO. : Des. 432,934
DATED : October 31, 2000
INVENTOR(S) : W. R. Simbeck et al.

It is certified that error appears in the above-identified patent and that said Letters Patent is hereby corrected as shown below:

On the Title Page

In column 1, item [73], delete "Management" and substitute --Measurement-- in its place.
